ELISHA S. BURLINGAME, OF UXBRIDGE, MASSACHUSETTS.

Letters Patent No. 94,470, dated September 7, 1869.

IMPROVEMENT IN MECHANISM FOR HOLDING BOLSTERS IN SPINNING-MACHINES.

The Schedule referred to in these Letters Patent and making part of the same.

To all whom it may concern:

Be it known that I, ELISHA S. BURLINGAME, of Uxbridge, in the county of Worcester, and Commonwealth of Massachusetts, have invented a new and improved Device for Holding the Spindle and Bolster in a Twisting or Spinning-Frame; and I do hereby declare that the following is a full and exact description thereof, reference being had to the accompanying drawings, and to the letters of reference marked thereon, making a part of this specification, in which—

Figure 1 represents a perspective view of the spindle, with the improved bolster and spring-collar as applied to the spinning-frame. A is the bolster, B the spring-collar, and C the step for the spindle.

Figure 2 is the spring-collar B, detached from the bolster.

Figure 3 represents the bolster in full and in sections, showing the shoulder, which rests on the upper part of the rail, and the groove for the spring-collar for the under side of the rail of the frame.

Figure 4 represents the step for the spindle in full, and also section, detached from the rail.

This invention consists in a new and improved construction of devices, as hereinafter described, for holding the spindle and bolster in twisting and spinning-frames. The bolster is used for the purpose of holding the spindle in its proper position, when in the operation of spinning and doffing. In order to take the spindle out of the frame, the bolster must be slipped out of the socket, and this is much easier done by the use of the spring-collar than the set-screw. The usual way of holding the bolster is by set-screws, which are liable to get loose, and make bad work with the spinning. If the screw is set too tight, it will indent the

bolster, which is made of soft metal, thus cramping the spindle. If it is set too light, the bolster is drawn out of its place in pulling off the bobbins. The spring-collar is a simple and sure means of fastening, is easily adjusted, lessens the expense of a spinning-frame from fifty to seventy-five dollars, overcomes all the objections found in the use of set-screws, and can be applied to any frame now in use.

To enable others skilled in the art to make and use my invention, I will proceed to describe its construction and application.

The bolster A is made of brass or soft metal, such as is commonly used for spindle-bolsters, turned and fitted into the socket of the rail of the spinning-frame, with a shoulder, as seen in fig. 3, to rest on the upper side of the rail in the socket, and it is also fitted to receive the spindle at its proper place in the rail.

A groove is cut round the bolster, as seen also in fig. 3, to receive the spring-collar B, as seen in fig. 1.

The spring-collar B is formed as seen in fig. 2, and made of spring-steel, rolled out round or square, formed as seen in fig. 2, and sprung round the bolster in the groove, as seen in fig. 1, holds the bolster and spindle securely and nicely.

What I claim, and desire to secure by Letters Patent, is—

The combination, with the bolster-rail, of the grooved bolster A and spring-collar B, when both are constructed and applied substantially as and for the purpose herein described.

ELISHA S. BURLINGAME.
